Assistant Examiner — Andrew T Nemeth

(57) **CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of another embodiment thereof; and, FIG. 3 is a front view of another embodiment thereof. The broken lines in the figures illustrate a display screen or portion thereof that forms no part of the claimed design.
